UNITED STATES PATENT OFFICE.

BASIL RUYSDAEL, OF NEW YORK, N. Y.

OPENING DEVICE FOR WRAPPED BOXES.

1,221,911.

Specification of Letters Patent. Patented Apr. 10, 1917.

Application filed December 31, 1915. Serial No. 69,695.

To all whom it may concern:

Be it known that I, BASIL RUYSDAEL, a citizen of the United States of America, residing in New York, in the borough of Manhattan, county and State of New York, have invented certain new and useful Improvements in Opening Devices for Wrapped Boxes, of which the following is a specification.

- 10 The present invention relates to improvements in opening devices for wrapped boxes, and particularly boxes such as are used for cigarettes, articles of food, medicinal preparations, etc., where such boxes are hermetically sealed to protect the contents by being wrapped and sealed in paraffined paper or the like. An object of the invention is to provide means surrounding the box and applied to the wrapper in such manner as 15 to enable the wrapper to be readily and conveniently removed from the package. As is well known such packages wrapped in the usual way, because of the nature of the material forming the wrapper and the secure 20 manner in which the same is pasted prove very hard to open, requiring either scratching with the finger nail, which is very disagreeable to some persons, and would be impossible should the person be wearing gloves 25 30 without the removal of the gloves, or the use of a knife or other sharp instrument, which is not always convenient. Another object is to provide such means which will not add materially to the cost of the wrap- 35 per and will be comparatively simple to apply.

With these and other objects in view my invention is shown in the accompanying drawings and will be hereinafter more fully 40 described with reference thereto and finally pointed out in the claims.

In the accompanying drawings.

Figure 1 represents a perspective view of a wrapped package in the form of a cigarette box embodying this invention.

Fig. 2 represents a longitudinal vertical section thereof.

Fig. 3 represents a transverse section of a fragment thereof.

50 Similar reference numbers indicate corresponding parts in the different figures.

The invention is illustrated as applied to a box for containing cigarettes. The box body 10 is provided with an upright flange 11 which is flush with the inner face of the

box and forms a recess at the outer face thereof about equal to one half the depth of the box. The lid 20 is provided with a downright flange 21, which shuts over the upright flange 11 of the body flush with 60 the outer face of said body and leaves a space between itself and said upright flange 11. A label 30 is disposed on one end of the box on the outer face thereof and covers the joint between the flange 21 of the box 65 cover and the body of the box. A wrapper 40 composed of paraffin paper or other suitable material, incloses the box. This wrapper has an inner folded flap 41 which extends downward from the top of the box 70 over the joint between the flange 11 and the body 10 and an outer folded flap 42 which extends upward from the bottom of the box and shuts over the flap 41 and extends above the joint between the lid and body of the 75 box. A revenue stamp 50 is pasted to the front of the box on the outside of the wrapper and covers the joint between the lid and body of the box.

A band 60 is disposed between the flanges 80 11 and 21 of the body and lid respectively and covers the joint between them along one end of the box, along the front thereof and half way along the opposite end of the box; thence it is passed downward between the 85 inner folded flap 41 and the body of the box, thence upward between the inner flap 41 and the outer flap 42 and has an extension 61 projecting above the upper edge of the outer flap 42 at one end of the box 90 as shown in Fig. 1.

In the use of this device for opening the box, the projecting tab 61 of the band 60 is grasped and pulled and said band is drawn and the end flaps 41 and 42 are torn 95 open, thence the wrapper is severed along the joint of the box body and lid from one end of the box to the other, across the front thereof and across the labeled end thereof, severing the revenue stamp 50 and 100 the label 30 successively.

I have illustrated and described a preferred and satisfactory form of my invention, but it is obvious that changes may be made therein within the spirit and scope 105 thereof as defined in the appended claims.

I claim:

1. A wrapped package comprising a box body having an upright flange, a cover therefor having a downright flange inclos- 110

ing the upright flange of said body, a wrapper inclosing said members, and a band disposed between said flanges and provided with a downward extension between the body of the box and the inner flap of the wrapper, an upward extension between the inner and outer flaps of the wrapper and a tab projecting above said outer flap.

2. A wrapped package comprising a box
10 body having an upright flange, a cover therefor having a downright flange inclosing the upright flange of said body, a wrapper inclosing said members, a label over said wrapper at one end of said package, a stamp over said wrapper across
15 the joint between said cover and body, and a band disposed between said flanges

along the label end of the package, along the stamp side thereof and along a portion of the opposite end thereof, said band being provided at the last named end with a downward extension between the body of the box and the inner flap of the wrapper, an upward extension between the inner and outer flaps of the wrapper and a tab projecting above said outer flap.

In testimony that I claim the foregoing as my invention, I have signed my name in presence of two subscribing witnesses.

BASIL RUYSDAEL.
